UNITED STATES PATENT OFFICE.

JOHN LANDRICHINGER, OF BAUXITE, ARKANSAS.

WHEAT CLEANER.

Application filed July 23, 1921. Serial No. 486,972.

To all whom it may concern:

Be it known that I, JOHN LANDRICHINGER, a citizen of the United States, residing at Bauxite, in the county of Saline 5 and State of Arkansas, have invented certain new and useful Improvements in Wheat Cleaners, of which the following is a specification, reference being had to the accompanying drawings.

10 This invention relates to machines for cleaning and separating wheat, and particularly to that class of machines wherein the wheat is subjected to the action of an agitator or beater to detach the outer coating 15 of the wheat and is then subjected to the action of a blast of air and to a screening action whereby to separate the chaff from the wheat and the bran therefrom.

The general object of my invention is to 20 provide a machine of this character wherein the wheat is subjected to one continuous action from start to finish, tending to the detachment of the chaff and to the detachment and separation of the bran from the wheat, 25 and whereby the normal wheat is separated from the very fine grains, the ordinary wheat then being sent to the burrs, the bad wheat being separated at this point from the good wheat.

30 A further object is to provide a construction of this kind wherein the wheat, after being subjected to the action of a beater and being dehulled and the bran and other foreign substances separated therefrom, passes 35 down onto a foraminous separator, through which passes a blast of air drawing off from the separator the bran, dust and other foreign substances and leaving the good wheat to travel along the separator to the point 40 of eventual discharge, the small and faulty ends of the wheat grains dropping through the separator and being eventually discharged therefrom, thus thoroughly cleaning the wheat so that while the wheat is 45 travelling along the separator it is submitted to the action of a blast of air which carries off the dust, dirt, chaff and other foreign matter and at the same time the small ends of the wheat or "cream of wheat" dropping 50 through the separator and thus being separated from the good wheat.

Another object is to provide a construction of this kind which is compact, may be operated with a relatively small amount of 55 power, and which is thoroughly effective for the purpose intended.

Still another object is to provide means whereby the air suction may be regulatably controlled.

My invention is illustrated in the accompanying drawings, wherein:

Figure 1 is a side elevation of a wheat cleaning and separating machine constructed in accordance with my invention, one end of the machine being broken away;

Figure 2 is an end view of the machine;

Figure 3 is a longitudinal sectional view thereof;

Figure 4 is a section on the line 4—4 of Figure 3;

Figure 5 is a fragmentary detail view of the manner in which the flannel web 45 is plaited;

Figure 6 is an end view of the machine with the trunk 35 removed;

Figure 7 is an inside face view of the trunk 35;

Figure 8 is a longitudinal horizontal sectional view through the machine taken on a plane just below the partitions 40, the separator being partly broken away;

Figure 9 is an enlarged vertical sectional view through the main frame and the separator supporting frame, showing the manner in which the separator supporting frame is mounted for adjustment;

Figure 10 is a section on the line 10—10 of Figure 9.

Referring to these drawings, and particularly to Figure 1, it will be seen that my wheat separator comprises an outer casing 10 having supporting legs 11 which form part of the frame of the casing and having bearings 12 for the support of a beater shaft 13 at its upper end. Extending along the bottom of the casing and supported by the legs 11 is a trough-shaped conveyor chute 14 within which operates a screw conveyor 15, the trough 14 in which the screw conveyor operates being provided at its discharge end with a discharge opening 15a. The screw conveyor is mounted upon a shaft 16 carrying a beveled gear wheel 17 meshing with a beveled gear wheel 18 mounted upon a transverse shaft 19 supported in suitable bearings at one end of the machine.

Mounted upon the frame of the machine within the casing 10 and disposed at the rear of the machine is a cylindrical beating chamber 20 which may be of thin sheet metal, and the interior face of this chamber is transversely corrugated. The inner face of the

chamber is lined with a lining 21 which is preferably formed of artificial, stone-like material, in which emery or material of the same character is predominant so that the 5 lining of the interior of the chamber 20 is rough as well as corrugated. It will be understood that the thin sheet metal from which the chamber is made need not be corrugated itself but that the material 21 is to 10 be formed with corrugations.

The shaft 13 extends into the chamber, and mounted upon the shaft is a beater consisting of the longitudinally extending blades 22 and the radial arms 23 extending from the 15 shaft and supporting these blades. Of course, suitable bearings are provided for the shaft. There is an entrance opening 24 at the forward end of the chamber 20 and at the upper portion of this chamber this entrance opening communicates with an upwardly and forwardly extending chute 25 whereby the wheat is discharged into the chamber. The forward end wall of the chamber is also provided with an auxiliary 20 or supplemental discharge opening 26 acting as a wheat escape when the beater chamber 20 is clogged. At the rear end of the chamber 20 there is a discharge opening 27 opening into a vertical chute 28 which, at its 25 lower end, has a discharge opening provided with a door or valve 29.

Forward of the beater chamber 20 there is disposed a suction fan chamber 30 within which is disposed a suction fan 31 mounted 35 upon a transverse shaft 32. This fan may be of any suitable character but is illustrated as provided with radially extending blades. The exterior end of this shaft is provided with a pulley 33 whereby the fan may 40 be driven. This fan takes in air through the machine and discharges air upward through a port 34 which opens from one end of the machine. One end of the fan chamber 30 is formed by the upwardly extending front 45 wall 35 of the machine. Disposed below the beater chamber 20 and the fan chamber 30 and spaced from the bottoms of these chambers are a plurality of compartments 36, 37, 38 and 39 which may be of any desired number, these compartments being divided from 50 each other by transverse partitions 40. The lower edges of the partitions 40 are upwardly and medially inclined, (Figure 4) and disposed below these partitions 40 and extending longitudinally beneath all of the 55 compartments 36, 37, 38 and 39 are a series of transversely extending troughs or ducts 41 which are U-shaped in cross section and preferably made of sheet metal, these troughs 60 extending upward toward the medial line of the machine from both sides, as shown in the sectional view in Figure 4. These troughs or ducts 41 are spaced from each other, leaving spaces 42 between the ducts, and at their 65 lower ends discharge into longitudinally ex-

tending, lateral troughs 43. The troughs 43 and the ducts 41 are made substantially integral with each other and as one element and are flexibly supported on the sides by webs of textile material 44 which are attached at 70 their upper edges to the side walls of the machine and at their lower edges are attached to the outer walls of the troughs 43, and attached to the partitions 40 and extending downward in close proximity to the 75 ducts 41 are transverse cloth strips 45 which may be attached at their lower edges to the flanges of the adjacent duct 41. Thus the structure comprising the ducts 41 and the troughs 43 is flexibly supported so that it 80 may be oscillated or jarred. Preferably the strips of cloth 44 and 45 will be of material on the order of canton-flannel with a relatively long nap and plaited, as in Figure 5.

The agitator structure composed of the 85 ducts 41 and the troughs 43 is formed below the ducts 41 with guides 46, on which guides is supported a longitudinally extending, drawer-like separator 47. This consists of a rectangular frame, the upper face of which 90 is covered with perforated sheet metal 48, while the lower face is formed of a perforated metal sheet 49. This perforated metal sheet 49 terminates short of the forward end of the frame 47 and is attached to 95 a transverse cross bar 50. The agitator 47 is divided transversely and longitudinally by a plurality of partitions 51. The transverse partitions 51 extend downward from the screen 48 but do not reach the perforated 100 metal 49 so that a space 52 is left between the lower edges of the transverse partitions 51 and the perforated metal 48. In each of the compartments 53 formed by the partitions 51 there is disposed a plurality, preferably 105 two, rubber balls 54 which in actual practice will be about $\frac{1}{2}$ " in diameter and will rest upon the perforated metal sheet 49. These balls, it will be understood, do not fill the compartment 53 but are spaced a sufficient 110 distance from each other so that the balls will oscillate as the separator 47 is reciprocated. The wheat which is delivered from the duct or chute 28 onto this separator plate 48 at the rear end thereof is gradually 115 worked forward until the wheat is eventually discharged downward from the forward end of the separator which projects into the trunk 35. The rubber balls in the several compartments keep the perforated 120 plates of the separator from choking as the wheat passes over the plates so that the air blast can pass through the foraminous plates and thereby separate the foreign matters from the wheat, these rubber balls moving 125 around in the small compartments and beating and striking against the upper screen 48 and the lower screen preventing the wheat from sticking in the perforations, which would prevent the air from passing freely 130

through the separator. The clamp bolt 55 rigidly connects the separator with the trough and duct structure formed by the ducts 41 and troughs 43. This structure is 5 reciprocated by crank shaft 56 engaging the arms 57 projecting from a cross bar 58 of the agitator frame, there being cloth strips 59 attached to the exterior of casing 10 across the end thereof and at their edges to the 10 cross bar 58. The crank shaft 56 is driven as will be later stated.

Opening into the top of each compartment 36, 37, 38 and 39 is a wind duct 60. Each 15 of these ducts extends upward from its corresponding compartment and then forward and opens at its forward end into the wind trunk 35, these wind ducts 60 having a width approximately equal to the width of the machine within the walls of the casing 10 and 20 being made of sheet metal. At their forward ends the wind ducts turn upward at their intersection with the trunk 35 and at their ends which open into the compartments 36, 37, 38 and 39 the ducts are provided with 25 valves 62 which are pivotally mounted on trunnion shafts or equivalent means, and each valve is provided with a handle 63 disposed upon the exterior of the machine, this handle operating over a suitable arcuate 30 rack so that the valves may be shifted to control the amount of suction exerted on material in the corresponding compartment.

The reason for providing separate compartments 36, 37, etc., above the separator 35 and connecting these separate compartments by separate ducts 60 to the fan chamber is that by this means the suction through the 40 entire length of the separator may be controlled for various parts of the separator or this suction made uniform for the entire length of the separator. Furthermore, by this means the suction is rendered more directly vertical through the separator than it otherwise would be as if there was one long 45 chamber above the separator and the ducts 60 were omitted the air would pass up through this separator more strongly and have a greater force in that portion of the separator immediately below the fan than it 50 would at that portion of the separator remote from the fan, and furthermore, the air would tend at that portion of the separator remote from the fan to pass diagonally upward instead of being drawn vertically 55 through the separator.

In order to provide means for leveling the separator, I pivotally connect to the separator the upwardly extending links 64, there being four of these links at opposite sides 60 and at opposite ends of the separator. The links on one side of the machine are swingingly mounted upon upright supports 65 which are attached to the frame of the machine, but the links 64 on the opposite side 65 of the machine at their upper ends swing-

ingly engage vertically extending members 66 in the form of strips (Figure 9) which each extend through a slot in the frame of the machine, and the lower end of each strip is upwardly and outwardly curved, as at 67. 70 The strips 66 are therefore mounted for vertical movement, and for the purpose of adjusting these strips vertically I pivot to the end 67 of the strips 66 the vertically extending handles 68 which extend upward 75 through slotted guides 69, these guides not only being formed with a longitudinally extending, vertical slot 70 but with a longitudinally extending, horizontal slot 71. Wing bolts 72 attached to the handle 68 extend out 80 through the slots 71. It will, therefore, be seen that the handle 68, while it may be shifted longitudinally, cannot be vertically shifted bodily, but it will be further seen, however, that if the handle 68 is shifted longitudinally in the slot 70 in one direction, it will tend to draw upward on the lower end 67 of the strips 66 and shift these strips vertically to a small degree. By adjusting these handle member 68 the separator may be 85 leveled and then the wing nuts 72 may be tightened so as to hold the separator in its leveled position, the links 64, however, permitting the separator to be reciprocated by means of the crank shaft 56, as heretofore 90 described.

Preferably the vertical strips 66 operate between rollers 66^a carried by members 67^a adjustably disposed between tracks 68^a, these tracks being supported by vertical tracks 100 69^a attached to the frame of the machine in any suitable manner. These rollers, of course, provide for a relatively easy movement of the vertically shiftable supporting members 66, the rollers, however, preventing 105 any lateral play of the members 66. While the construction which I have described has been thoroughly effective for the purpose of leveling the separator, I do not wish to be limited to this, as it is obvious that other 110 means for leveling the separator might be substituted for that shown.

The trunk 35, as illustrated in Figure 3, is attached to one end of the frame 10 and extends vertically downward from the fan 115 chamber 30, and this fan chamber opens into the upper end of the trunk 35. Below the intersection of the ducts 61 with the trunk 35 this trunk is formed, as shown in Figure 7, with a pair of vertically extending partition walls 73 laterally spaced from each other and extending to the lower end of the trunk and spaced a slight distance from the side walls of the trunk. Extending transversely between these vertical walls 120 73 is a vertical wall 74 which is parallel with the end wall of the trunk, and adjacent the upper end of this wall 74 there is provided the downwardly and laterally inclined chutes 75 which discharge into spouts 125 130

76 upon the exterior of the trunk on each side thereof. Between the end wall of the trunk 35 and the wall 74 an air space 77 is formed, the passage of air through this space being controlled by a valve 78 mounted upon a spindle 79, one outer end of which is provided with a handle 80 whereby the valve may be shifted. Between the partitions 73 and the side walls 10 of the trunk and disposed on a line with the lower end of the partition 74 are horizontal partitions 81. Spaced from the walls 75 is a vertically extending partition 82 and between the partitions 73 and the side walls 15 of the trunk and spaced from the horizontal partitions 81 are the vertical partitions 83 which extend downward to the lower end of the trunk. A space 84 is thus left between the partitions 74 and 82 into which 20 the discharge end of the separator 47 extends, this separator 47 discharging forward of the partition 82. A chute 85 receives the wheat discharged from the separator and conducts it out of the lower end 25 of the trunk. The channels or troughs 43 discharge into the spaces 86 and into vertically extending spouts 87 discharging at the lower end of the machine. Preferably the trunk from a point in front of the space 30 84 to a point above the chute 85 is provided with a door 88 having a glass pane whereby the wheat being discharged from the separator may be observed, and this door is also provided with two small glass panes 89 opposite the spaces 86 from which the discharge of bran may be observed. It will be noted that the outer wall of the chamber 30 projects into the upper end of the trunk 35 and opens into this trunk. Thus it will be 35 seen that the suction fan 31 acts to draw air upward from the space between the partition 74 and the front wall of the trunk and also acts to draw air through the ducts 61 and that this air is regulated and controlled 40 by means of the valves 62 and of the valve 78.

The machine is driven preferably by power, and to this end power may be communicated to the shaft 13 by means of a 50 pulley 90. From this shaft 13 power is taken by means of the pulley 91 and belt 92 to a pulley 93 mounted upon the shaft 56. This shaft carries upon it a pulley 94 from which a belt leads to a pulley 95 mounted upon the shaft 19. The fan 31 is operated by means of a belt 96 engaging a pulley 97 on the shaft 56, and the pulley 33 on the fan shaft. Obviously I do not wish to be limited to any particular means, however, for driving these shafts.

The general operation of my mechanism is as follows:—The wheat to be treated is fed into the hopper 25 and discharges into the cylinder 23 where it is violently agitated, stirred up and beaten by the rotating

beaters therein and subjected to a scouring action by contact with the rough, corrugated, inner surface of the casing. In this chamber the wheat is dehulled and the grain separated from the bran and other foreign substances and the wheat travels gradually from the inlet end of the casing to the outlet thereof and is discharged downward through the duct 27 onto the separator plate 48. The wheat travels along the separator plate and is at this time exposed to the air blast which comes from below up through the perforations in the plates or screens of the separator and this air blast effects the cleaning. As the wheat passes over the perforated plate 48 the small or fine wheat and the ends of the wheat grains or screenings drop through the perforations in the separator and are deposited in trough 14. The good wheat or ordinary sized wheat travels over the screen of the separator and the suction of the air passing upward through the separator carries the bran, chaff, dirt and other foreign matters into the compartments 36, 37, 38 and 39. Here the chaff and bran fall downward onto the inclined ducts 41 and pass down these ducts into the channel or chute 43. The wires 98 keep the machine from getting clogged up or choking and cause the wheat to move on as the parts are oscillated. The dust, chaff, etc., are drawn upward by suction and discharged into the wind trunk 60, from whence they are carried through the trunk 65 and out through the discharge opening 34. The object of 100 valves 62 is to regulate the air according to whether the wheat is damp or dry so that proper air suction can be had.

As the wheat is discharged into the trunk 35 it is subjected to air which rushes upward 105 to the fans, and any faulty wheat, that is screenings, which may have accompanied the good wheat is carried upward and against the valve 78 which constitutes a deflector and then falls downward upon the inclined 110 chute 75 and is discharged through the spouts 87. The bran is caught in the series 115 of downwardly inclined ducts 41 and discharged into the channels 43, from which channels or troughs the bran is discharged into the downwardly extending spouts 87. The fine wheat, as before stated, is discharged into the trough 14 and carried by the conveyor 15 to the end of the trough where it discharges downward to a lower 120 floor to be further treated. The chaff, dust and other foreign matter, as before stated, is drawn upward through the ducts 61 and discharged out through the opening 34 of the fan chamber 30. This machine completely 125 scours and cleans the wheat prior to the passage of the wheat to be ground, fully separates the normal wheat from grains of very small size and from faulty wheat and from bran so that the faulty wheat is caught sep- 130

arately, the bran is caught separately, the very small wheat is separately caught, wheat of a normal character is separately discharged, and the chaff and dust blown out 5 of the machine.

The separator and allied parts will reciprocate at about 375 oscillations per minute and it should have a stroke of about $\frac{1}{2}$ ". The rubber balls are about $\frac{3}{4}$ " in diameter 10 and these rubber balls bouncing around within the several compartments in which they are confined act to prevent the perforations of the screen from being choked up or blocked.

15 This machine has many advantages over other machines known to me, particularly in that it is a combination of two machines in one. This machine detaches the chaff and bran from the wheat and prepares the wheat 20 ready so that it can be ground into flour. The bran is also cleaned ready for use and no dust is left in the bran, as this is forced out by the air blast. Should there be any oats or rye in the wheat, this machine separates 25 it out. This machine further treats the wheat by breaking or taking off in some way the ends of the grain which are unfit to be ground into flour.

While I have illustrated what I have 30 found to be a thoroughly effective form of my invention, yet I do not wish to be limited thereto, as it is obvious that many changes might be made in the details of construction and arrangement of parts without departing from the spirit of the invention.

I claim:—

1. In a wheat cleaner, a reciprocatable, 40 horizontally disposed, foraminous separator upon which the wheat to be cleaned is discharged, a casing formed to provide a plurality of compartments above the separator, air suction means, and a plurality of ducts leading one from each compartment to the air suction means, each duct having a length 45 equal to the width of the compartment but having a small width relative to the length of the compartment.

2. In a wheat cleaner, a reciprocatable, 50 horizontally disposed, foraminous separator upon which the wheat to be cleaned is discharged, a casing formed to provide a plurality of compartments above the separator, air suction means, and a plurality of ducts leading from the upper ends of the several 55 compartments to the air suction means, each of said ducts extending transversely across the entire width of the compartment, each duct having a width small relative to the length of the compartment and being provided with a valve disposed adjacent the entrance of the duct whereby to control the air current passing up through the separator.

3. In a wheat cleaner, a reciprocating, 60 horizontally disposed foraminous separator, a plurality of transversely extending chutes

mounted in spaced relation above the separator, laterally disposed troughs mounted in connection with the separator and into which the chutes discharge, means for giving a common reciprocating motion to the troughs, 70 chutes and separator, a compartment of which the separator and the laterally extending troughs form the bottom, suction means, an air duct extending from the top of said compartment to the suction means, and 75 a valve controlling passage of air to said air duct.

4. In a wheat cleaner, a reciprocating, horizontally disposed foraminous separator, 80 a plurality of transversely extending chutes mounted in spaced relation above the separator, laterally disposed troughs mounted in connection with the separator and into which the chutes discharge, means for giving a common reciprocating motion to the 85 troughs, chutes and separator, a compartment of which the separator and the laterally extending troughs form the bottom, suction means, an air duct extending from the top of said compartment to the suction 90 means, a valve controlling passage of air to said air duct, and a deflector mounted below the inlet of the air duct in spaced relation thereto.

5. In a wheat cleaning mechanism, laterally disposed troughs mounted for reciprocating motion, a plurality of transversely extending chutes downwardly inclined from a medial plane into said troughs, a foraminous separator operatively supported upon 100 said troughs and below said chutes, means for discharging wheat onto one end of the separator, means at the other end of the separator whereby the wheat may be discharged, a casing formed to provide a plurality of 105 compartments above the separator, the chutes and troughs traversing said compartments, air suction means, and a plurality of ducts leading from the air suction means into the upper ends of the several compartments, 110 each duct extending transversely across the corresponding compartment and having a cross sectional diameter small relative to the cross sectional area of the compartment.

6. In a wheat cleaner, a supporting frame 115 having side and end walls, a series of transverse partitions extending across the supporting frame forming compartments closed at the top and open at the bottom, a longitudinally reciprocating frame disposed 120 immediately below the lower ends of said partitions, laterally disposed, longitudinally extending troughs carried upon said reciprocating frame, a series of transversely extending chutes carried upon said troughs and 125 discharging thereinto, said chutes being laterally inclined downward to the troughs and being spaced from each other, a foraminous separator mounted between said troughs and below the chutes, means for discharging 130

grain onto one end of the separator, means at the other end of the separator whereby grain may be discharged therefrom, strips of flexible material connecting said troughs 5 to the sides of the casing, the strips of flexible material depending from the partitions and extending to the chutes, a series of wind ducts disposed above the compartments, each opening into one of said compartments 10 at one end, a suction fan including a casing to which the other ends of the air ducts are operatively connected, a conveyor disposed below the whole length of the separator and receiving grain discharged through the bottom thereof, and means for reciprocating the separator, the troughs and chutes.

7. In a wheat cleaner, a longitudinally reciprocatable, flexibly supported separator having a foraminous top and bottom and 20 divided into a plurality of relatively small compartments by transverse and longitudinally extending partitions, the partitions extending downward from the top of the separator but being spaced from the bottom 25 thereof, means for causing a blast of air to pass upward through the separator, means for reciprocating the separator, and means for leveling the separator.

8. In a wheat cleaner, a supporting frame, 30 a longitudinally reciprocatable, foraminous separator mounted upon the frame, a wind

trunk extending upward at the forward end of the frame and into the lower portion of which the separator discharges, a suction fan including a housing into which the upper end of the trunk opens, a deflector extending at an angle across the wind trunk above the point of discharge of the separator, and chutes rearward of said deflector and traversing the wind trunk into which the deflected matter is discharged.

9. In a wheat cleaner, a supporting frame, a longitudinally reciprocatable separator, a vertical wind trunk forming the forward end of the frame and into the lower portion 45 of which the separator discharges, means connected to the upper portion of the wind trunk for drawing air upward through the wind trunk, downwardly and laterally inclined chutes disposed within the wind trunk 50 above the point of discharge of the separator, and a member oscillatably mounted within the wind trunk and traversing the same and extending transversely thereof and adapted to deflect upwardly moving screenings into said receiving chutes and to constitute a valve controlling the passage of air upward through the lower portion of the wind trunk.

In testimony whereof I hereunto affix my 60 signature.

JOHN LANDRICHINGER.
